UNITED STATES PATENT OFFICE.

ROBERT A. WILLETT, OF SOUTH AMBOY, NEW JERSEY.

BRICK-MACHINE.

SPECIFICATION forming part of Letters Patent No. 390,110, dated September 25, 1888.

Application filed August 18, 1887. Serial No. 247,276. (No model.)

To all whom it may concern:

Be it known that I, ROBERT A. WILLETT, of South Amboy, in the county of Middlesex and State of New Jersey, have invented a new and Improved Brick-Machine, of which the following is a full, clear, and exact description.

Reference is to be had to the accompanying drawings, forming a part of this specification, in which similar letters of reference indicate corresponding parts in all the figures.

Figure 1 is a broken plan view of my new and improved brick-machine. Fig. 2 is a side elevation of the same, the lever being partially broken away. Fig. 3 is a sectional elevation taken on the line *x x* of Fig. 1. Fig. 4 is a transverse sectional elevation taken on the line *y y* of Fig. 3. Fig. 5 is a detailed sectional view of the two main power-levers, the cams and connections for operating them, the molds, and plungers. Fig. 6 is a detailed view showing the mechanism for operating the "up-take."

The invention will first be described in connection with the drawings, and then pointed out in the claims.

A A represent the main frame of the machine, and B represents the main power-shaft, which is provided with a pinion, B', which meshes with the gear-wheel B² on the shaft B², for turning the said shaft. The shaft B² is provided with the two pinions B⁴ B⁴, which mesh with the large gear-wheels C C, secured upon the heavy shaft D for revolving the same, and the cams secured thereon for operating the power-levers of the machine, as hereinafter described.

E E represent the molds, in which the clay is compressed into the form of bricks by the upper plungers, F F, and the lower plungers, G G.

The clay is fed to the molds E from a hopper, H, (see Fig. 3,) by a sliding feed-box, J, which is reciprocated from a position in line with the bottom of the hopper to a position immediately over the molds E by means of a connecting-rod, J³, and crank J², secured to the shaft J', which is rotarily reciprocated, as hereinafter described.

The lever K is for reciprocating the uptake M. It is placed loosely upon the shaft J', and

is connected to an arm on the uptake by a connecting-rod, K², and is reciprocated by the cams L L, secured to the spokes of the wheel C, (see Fig. 6,) acting upon the lever L', which is connected to the arm K² of the said lever K by the connecting-rod K⁴. The downward movement of the lever L' will thus swing the uptake M to the position shown in Fig. 3, while the upward movement of said lever will permit the uptake to drop to the position shown in Fig. 2.

The uptake M is secured to the heavy shaft M' and acts in connection with the upper plungers, F, and the cross-bar F', to which they are attached, and its object will be fully explained below.

The lower plungers, G, are attached to the cross-bar G', which rests in the center upon the heavy spring G², which normally holds said cross-bar and plungers somewhat elevated from the saddle-pieces g g, as shown in Fig. 2, until the plungers F are let down on the material in the molds E. Then the loose bar G' is driven down into the saddles g g by the descent of the upper power-levers, P, so that said spring will take the first and second pressures applied to the brick material in the molds, which first pressure settles the material and partially excludes the air and fits the material for the following heavier pressures.

The saddle-pieces g are held at the bottom of the heavy yokes N at each side of the machine, which yokes depend from the heavy levers O O, and the saddles g are made vertically adjustable by the wedges g' g', for making bricks of different and uniform thicknesses. The wedges g' g' are adapted to be moved by screws g² g², shaft g³, pinions g⁴, and worms g⁵ g⁵ and hand-wheel g⁶, so that the adjustment can take place without stopping the machine.

The heavy levers O O are fulcrumed at their forward ends upon the fixed studs O⁴, and the upper heavy levers, P, are connected to the heavy links or connecting-rods O' O', which are connected to the studs O⁴ and constitute swinging fulcrums of the levers P. The levers P act upon the heavy shaft M', which shaft is free to move vertically through a short space in slots in the main frame, and the downward movement of this shaft forces the cross-piece F' and the upper plungers, F, downward for

effecting the heavy final pressure upon the brick material in the molds. The levers O are operated by the cams O², secured upon the shaft D, while the upper levers, P, are operated simultaneously at the final pressure with the levers O in the opposite direction by the heavy cam P⁵. (See Figs. 1 and 5.) The said cam P⁵ is secured on the shaft D and acts upon the sliding frame P², which is connected to the two levers P by the heavy cross-piece P³ and shaft P⁴ and forces the levers P downward. The said levers P are lifted by the cams P' on shaft D acting against the rollers d', secured to the frame P², as shown in Fig. 3. Before the ascent of the levers O, permitted by the cams O², the upper plungers, F, are brought down, by means hereinafter described, on the clay in the molds E to give the material its first or initial pressure. Then the levers P are dropped down on the plungers F, giving the second pressure to the material. Their weight then drives the cross-bar G' down into the saddle-pieces gg, giving the third pressure to the material. Now the levers O are operated by the cams O², thereby lifting or tending to lift the upper levers, P, up by the material in the molds, imparting another pressure to the now partly-formed brick. The air is now thoroughly expelled from the clay, and the brick receives its final pressure by the cam P⁵ pulling the levers P down, and the cam O² holding the lever O in the position shown in Fig. 5.

As above stated, the upper plungers, F, are connected to the cross-piece F', which is held in slots in the main frame, and at the time of the discharge of the completed bricks and the recharging of the molds the said cross-piece and molds are elevated by the levers F², and this upward motion must be considerable to admit the feed-box beneath the plungers. The levers F² are connected to the cross-piece F' by the links F³, and are attached to the shaft F⁴, which is rotarily reciprocated by the lever F⁶, acted upon by the cams F⁷, attached to the wheel C.

In order to avoid the necessity of lifting the heavy shaft M' the distance required to clear the plungers F from the feed-box J, I employ the uptake M, which, when the said plungers are lifted, is swung outward to horizontal position, as shown in Fig. 3, by the action of the lever K, as above described. The uptake remains in this position until the cross-piece F' and plungers F reach the clay in the molds on the downward movement caused by the levers F² F⁶ and cams F⁷. At this time the uptake is turned to vertical position by the movement of the lever K, as shown in Fig. 2, where its lower edge rests upon the upper surface of the cross-piece F'. At this time the heavy levers O are at rest and the levers P are moved downward, which moves the shaft M' downward and forces the upper cross-piece, F', downward, thus effecting an enormous pressure upon the material in the mold-boxes. The shaft J' is rotarily recip-

ated at the proper time by the cams L and connections K², K³, K⁴, and L', as shown clearly in full and dotted lines in Figs. 2 and 6. The 70 bricks, after being compressed in the mold-boxes E, are expelled by an upward movement of the lower plungers, G, and cross-bar G', produced by the lever Q, fulcrumed on shaft Q', said lever being acted upon by the cams 75 Q³ on the wheel C to raise the plungers G to a level with the top of the molds E. (See Fig. 1.) At this time the filling-box J is moved forward to fill the molds again, and this movement of the filling-box shoves the bricks out 80 upon the table T. The feed-box J is reciprocated from the shaft D by the two opposite cams J⁵ J⁶ acting through the yoke J⁷, lever J⁸, connecting-rod J⁹, and arm J¹⁰.

The quantity of material taken in the molds E 85 is regulated by the eccentric T', (shown in Figs. 3 and 4,) secured upon the shaft T² beneath the spring G². The shaft T² may be turned for causing the eccentric to lessen the drop of cross-bar G' and plunger G, thereby increasing or diminishing the amount of clay in the molds E at will.

It is well known that certain qualities of clay may be worked very rapidly, while others require a very slow pressure to produce the best 95 results. In order to adapt the pressure to the different qualities of clay, I attach to the cams P' the segments U, (shown in Fig. 5,) which retard the yokes P² and levers P in their descent, and thus cause a slow downward movement of the plungers in the mold-boxes. By removing these segments the instant the points d of the cams pass the rollers d' the yokes P² and levers P drop and instantly compress the clay; but when the segments are used the 100 curved outer edges thereof support the yoke and cause a slow downward movement.

Having thus described my invention, what I claim as new, and desire to secure by Letters Patent, is—

1. The combination, with the power-levers and shaft M', of the uptake M, means for reciprocating it, and the cross-piece F' and plungers F, substantially as described.

2. The shaft M', uptake M, cross-piece F', and followers F, in combination with the molds E, plungers G, cross-piece G', and spring G², which supports the said cross-piece and plungers, substantially as described.

3. The upper levers, P, the shaft M', sliding frame P², and levers O, linked to the said upper levers, P, and acted upon at their rear ends by the cam O², in combination with the uptake M, mold-boxes E, and the upper and lower plungers, substantially as described.

4. The cross-piece F' and followers F, and the levers F², for reciprocating the same, in combination with the pivoted uptake M and means for operating the same, substantially as and for the purposes set forth.

5. The levers O, provided with the heavy yokes N and fulcrumed on the studs O⁴, and arranged to lift the cross-piece G' and lower plungers, in combination with the upper le-

vers, P, links O', cross-piece F', plungers F, pivoted uptake M, and movable shaft M', substantially as described.

6. The links N, connected to the levers O and the cross-piece G', levers Q, and links Q², connecting the levers Q to the said cross-piece, in combination with the blocks g, placed in the said links, and the wedges g', and means, substantially as described, for moving the said wedges, substantially as described.

7. The combination, with the cross-piece G', plungers G, and spring G², of the eccentric T and shaft T², substantially as and for the purposes set forth.

15 8. The cross-pieces F', plungers F, uptake M, levers P, cam P' and the cam O², levers O, cross-head G', plungers G, and spring G², in

combination with cam P⁵, arranged to move the levers P toward the lever O, substantially as described.

9. The combination, with the cam P', of the removable segment U, substantially as and for the purposes set forth.

10. The feed-box J, placed beneath the hopper H, the molds E, and the plungers F G, in combination with the shaft J', arm J², connecting rod J³, arm J¹⁰, connecting-rod J⁹, lever J⁸, yoke J', and cams J⁵ and J⁶, secured upon the shaft D, substantially as described.
